ANSON W. MINER, OF WATERBURY, CONNECTICUT, ASSIGNOR TO THE WATERBURY
BRASS GOODS CORPORATION, OF WATERBURY, CONNECTICUT, A CORPORATION OF
CONNECTICUT

LIP-STICK OR LIKE CONTAINER

Application filed October 1, 1927. Serial No. 223,404.

This invention relates to a container, especially to a container for lip sticks or the like, although it is not necessarily limited to such use, and has for an object to provide 5 an improved container of this type which is extremely simple in construction, which may be manufactured and assembled at low cost, which will be reliable in operation, and will be so constructed as to in no way interfere with the filling operation.

With the foregoing and other objects in view, I have devised the construction illustrated in the accompanying drawing forming a part of this specification. In this 15 drawing,

Fig. 1 is a side elevation of a complete container in closed position.

Fig. 2 is a transverse section substantially on line 2—2 of Fig. 1.

Fig. 3 is a side elevation of the cover removed.

Fig. 4 is a side elevation of the casing removed from the cover.

Fig. 5 is a side elevation of the cosmetic 25 holder.

Fig. 6 is a longitudinal section thereof substantially on line 6—6 of Fig. 5.

Fig. 7 is a side elevation of the holder showing a slightly different construction but 30 with the lateral projection incomplete.

Fig. 8 is a similar view showing the projection completed, and

Fig. 9 is a longitudinal section substantially on line 9—9 of Fig. 8.

This container comprises the usual cover 35 closed at one end 11 and open at the other end to receive the casing 12. This casing is also closed at one end 13 and open at its opposite end to receive the cosmetic holder 14 and the cosmetic which may be a lip stick 15, eyebrow pencil or other goods. All of these elements are usually made of 40 relatively thin metal and may be of any shape in cross section desired, such as round, oval or any other shape. The casing 12 has a longitudinally extending slot 16 in its side wall to receive a lateral projection 17 extending outwardly from the side wall of the holder 14. This holder is of light metal 45 usually cupped, and the projection is cut

from the metal forming the holder leaving a tongue which is rolled outwardly upon itself, as shown in Figs. 5, 6, 8 and 9, to form a projection 17 which extends through the slot 16 and serves to shift the holder and the cosmetic carried thereby longitudinally of the casing. In the form shown in Figs. 5 and 6, the tongue is cut directly from the side wall of the holder by splitting these walls longitudinally a suitable distance from the open end of the holder. The tongue thus formed is rolled outwardly and backwardly upon itself, as shown in Figs. 5 and 6 to form the projection 17. In the form shown in Figs. 7, 8 and 9 the tongue is the same except that in forming the holder 14^a the tongue 20 is cut from the metal so that it projects beyond the open end of the holder. The projection 17, however, is formed in exactly the same way as in Figs. 5 and 6 by 55 rolling this tongue outwardly and backwardly upon itself. When finished in the form shown in Figs. 5 and 6 the projection will be spaced somewhat from the open end of the holder. While in the form of Figs. 7 to 9 it will be located right at the open end of the holder. In either case the tongue is integral with the wall of the holder and is in effect formed as an extension of the side wall thereof.

The slot 16 at the side of the casing opens through the open end of the side wall but is restricted adjacent this open end by the inward extensions 18 which prevent the projection 17 on the holder from sliding from the slot, and therefore, prevents accidental displacement of the holder from the casing. It is, of course, understood that the holder 14 carrying the cosmetic is slidable longitudinally in the casing to expose the cosmetic for use. The casing is also slid able longitudinally in the cover, and to prevent accidental separation of the cover and casing the casing is provided adjacent its open end and on the free portion on the side of the slot 16 with one or more outwardly extending nubs 19 which frictionally engage the inner wall of the cover under the resilient action of the metal of the casing, and there- 60 65 70 75 80 85 90 95 100

fore, tend to retain the cover and casing against accidental separation.

It will be apparent from the foregoing description that the device is very simple in construction and may be manufactured at low cost. It may also be easily and quickly assembled and filled with the cosmetic. The structure of the lateral projection 17 on the holder does not in any way interfere with the filling of the holder, and the various elements are held against accidental separation.

Having thus set forth the nature of my invention, what I claim is:

1. In a lip stick or like container, a thin resilient sheet metal casing open at one end having a longitudinally extending slot in its side wall opening through said open end and restricted adjacent said end, a cover enclosing said casing and in which the casing is slidable, raised nubs on the walls of the casing on opposite sides of the slot adjacent the open end of the casing and extending above the outer surface of the casing to frictionally engage the inner walls of the cover, said nubs being closely adjacent the restricted portion of the slot, and a cosmetic container slidable in the casing and having a projection on its side wall extending through said slot.

2. In a lip stick or like container, a thin resilient sheet metal casing open at one end having a longitudinally extending slot in its side wall opening through said open end and restricted adjacent said end, a cover enclosing said casing and in which the casing is slidable, a raised nub on the casing wall adjacent said open end at one side of the slot and extending above the outer surface of the casing to frictionally engage the inner wall of the cover, said nub being closely adjacent the restricted portion of the slot, and a cosmetic holder slidable in the casing and having a projection on its side wall extending through said slot.

In testimony whereof I affix my signature.

ANSON W. MINER.
